Specification for Design.

Patented Nov. 22, 1921.

Application filed July 5, 1921. Serial No. 482,611. Term of patent 14 years.

To all whom it may concern:

Be it known that we, KARL B. KILBORN and WILLIAM S. WOLFE, citizens of the United States, residing at Akron, Ohio, have invented a new, original, and ornamental design for a Tire, of which the following is a specification, reference being had to the accompanying drawing, forming a part thereof.

Figure 1 is a top plan view of a portion of the tire casing; and

Fig. 2 is a transverse section thereof.

We claim:

The ornamental design for a tire as shown.

KARL B. KILBORN.
WILLIAM S. WOLFE.
